UNITED STATES PATENT OFFICE

FRANK KUBERKA, OF VIRGINIA, MINNESOTA

LIFTING HOOK

Application filed May 16, 1931. Serial No. 537,945.

This invention relates to attachments for hoisting chains.

It is an object of the invention to provide an improved lifting hook for attachment to hoisting means, the hook being adapted to substantially enclose the chain when in inoperative position but to have such relation with the chain in operative position as to form means for engaging cable reels and the like whereby the same can be lifted.

A further object is to provide a lifting hook which can be readily inserted in an opening in the object such as cable reels when in inoperative position and which will comprise an effective engaging means by which the object can be safely lifted.

A further object is to provide a novel and improved device of this character which will be easy to operate and which will fulfill all requirements of practical operation.

With these and other objects in view, the invention may consist of certain novel features of construction and operation as will be more fully described and particularly pointed out in the specification, drawing and claims appended hereto.

In the drawing, which illustrates an embodiment of the device and wherein like reference characters are used to designate like parts—

Figure 1 is a sectional view taken substantially through the center of a cable reel showing the lifting hook of the present invention in position for lifting the same.

Figure 2 is a sectional view of a cable reel showing the lifting hook in position for insertion in the opening of the reel.

Figure 3 is an elevational view, parts being shown in section, of the lifting hook showing the same associated with a hoisting chain.

Figure 4 is a plan view of a lifting hook, and

Figure 5 is an end elevation of the hook shown in Figure 4.

Referring to Figures 3, 4 and 5 of the drawing, the lifting hook is shown as associated with a hoisting chain 10 forming part of a frame or other hoisting mechanism. The hook or cross member 12 is formed in a chan-

nel shape, as shown in Figure 5, and by means of a pin 14 extending transversely of the same and at substantially its mid-portion the member is pivotally attached to the chain, since the lower link 16 encircles the pin. For allowing free movement of the member 12 on the chain the bottom surface of the member is recessed as at 18 directly below the location of the pin.

Attached to one end of the member 12 is an operating chain 20, the link 22 being looped through an opening 24 formed in the member. The other end of the chain 20 is fastened to the main chain 10 by the engagement of end 26 with link 28.

In Figures 1 and 2 there is shown a cable reel of usual construction having a winding drum 30 and side members 32. Central openings 34 are provided at substantially the center of the reel, through which the lifting means of the present invention is adapted to be inserted for engaging the reel, whereby the same may be lifted.

Referring first to Figure 2, the member 12 is shown in vertical position, in which position it can be considered as forming a continuation of the main chain 10. Due to the channel-shaped cross section given to member 12 one end will enclose the portion of the chain 10 adjacent the pivot pin 14. In this position the member 12 can be inserted in an opening, provided the same is just slightly larger than the diameter of the chain 10.

When the hoisting mechanism has been lowered to an extent where the member 12 is located within drum 30 the member can be caused to assume a horizontal position with respect to the hoisting chain by means of the auxiliary operating chain 20. With the parts in this position upward movement can be imparted to the hoisting chain whereby the member 12 forms a lifting hook engaging the side member 32 at points adjacent the opening 34 and thus forms a secure and effective means whereby the cable reel can be safely lifted.

It will be apparent that by a reversal of the operations explained for inserting the member 12 the same can be readily disconnected from the reel and removed through opening 34.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

- 10 1. A lifting hook, comprising in combination, a chain or the like having connection to hoisting mechanism, a member pivotally secured to the lower end of said chain, said member being channel-shaped and having two
15 operative positions with respect to said chain, one position with the member at right angles to the chain whereby the same forms a hook, and the other position with the member extending longitudinally of the chain substantially enclosing the chain.
- 20 2. A lifting hook, in combination, a chain or the like having connection to hoisting mechanism, a member pivotally secured to the lower end of said chain, said member being
25 channel-shaped and permitting insertion in objects to be lifted when positioned longitudinally with respect to the chain and substantially enclosing the same.
- 30 3. In combination, a chain or the like, having connection to hoisting mechanism, and a terminal member secured to the lower end of said chain forming a hook with respect thereto, said terminal member when positioned longitudinally of the chain substantially
35 encloses the same whereby the member may be inserted and withdrawn from openings of a diameter substantially that of the chain.

Signed at Virginia, Minnesota, this 9th day
40 of May, 1931.

FRANK KUBERKA.
